DOORSTOP

Application filed June 18, 1928. Serial No. 286,099.

This invention relates to door stops for swinging doors or similarly mounted closure members of the type having provision for retaining the door in an open position and has for an object to provide a door stop of simple and inexpensive construction which operates automatically to hold the door against closing movement after it is opened, the holding means being in the form of a yieldable latching device which is adapted to be released by pressure on the door toward closing position so that it is unnecessary to operate the latch manually in order to close the door.

A further object of the invention is to provide a connection with a yieldable latching device, a manually operable locking member by which release of the latching means is prevented and the door may be positively locked in an open position.

A further object is to provide a door stop of the character above referred to which is composed of a minimum number of parts, which is inexpensive to manufacture and which may be easily applied to any hinged closure member.

A further object is to provide a door stop in which movements of the door are controlled by a pivoted stop member interposed between the door and door casing and having sliding engagement with a guide member which yieldingly engages the stop member and which has a portion formed for latching engagement therewith, the latching portion of the guide bar being yieldable when subjected to the thrust of the stop bar in either direction so that the door may be automatically latched and yieldably retained in open position.

A further object is to provide a manually operable locking member for holding the guide bar against movement so as to positively lock the door in open position and to so mount the locking member that in its normal position, it does not interfere with the movements of the guide bar.

With the above and other objects in view, the invention may be said to comprise the device as illustrated in the accompanying drawings hereinafter described and particularly

set forth in the appended claims, together with such variations and modifications thereof as will be apparent to one skilled in the art to which the invention appertains.

Reference should be had to the accompanying drawings forming a part of the specification in which:

Fig. 1 is a top plan view of the door and door stop with the top member or lintel of the door frame omitted, the door being shown in full lines in closed position and in dotted lines in open position.

Fig. 2 is an elevation looking toward the inner side of the door with the door closed, the locking position of the lock bar being shown in dotted lines.

Fig. 3 is a section taken on the line indicated at 3—3 in Fig. 2.

Fig. 4 is a section taken on the line indicated at 4—4 in Fig. 3.

Referring to the accompanying drawings, in which the invention is shown applied to an outwardly opening door such as a garage door, the door is indicated by numeral 1 and is mounted in a suitable frame of which a jamb 2 and lintel 3 are shown, the door being connected to the jamb 2 by means of hinges 4 to swing outwardly.

To the inner side of the door adjacent the upper edge thereof, there is attached a wear-plate 5 which is in the form of a flat metal strip secured to the face of the door parallel with and adjacent the upper edge thereof by means of screws 6. The wear plate 5 has attached thereto a guide bar 7 formed from flat resilient metal stock, the body portion of the guide bar being parallel with the wear plate and spaced outwardly therefrom and the outer end of the guide bar being bent inwardly at 8 and secured to the wear plate by means of a rivet 9 at a point adjacent the outer end of the wear plate. Adjacent its inner end, the wear plate carries an outwardly projecting pin 10 which extends through an aperture in the inner end of the guide bar 7, the aperture being slightly larger than the pin so that the inner end of the bar 7 can move freely on the pin toward and from the wear plate 5. The pin 10 carries a spring 11 which bears upon the outer face of the bar 7 to press the

same against the wear plate, the spring being retained on the pin by a nut 12 at the outer end thereof, which may be adjusted to properly tension the spring. A short distance from its inner end, the guide bar 7 is bent to provide a tapering projection 13 and a recess 14 between the projection and the pin 10.

A U shaped bracket 15 is attached to the under side of the lintel by means of screws 16 and this bracket has a central aperture 17 which receives one end of a stop bar 18, the stop bar 18 having an end portion 19 bent upwardly and laterally to provide a pivotal connection for the bar in the opening 17 of the bracket. The opposite end of the stop bar 18 has a downwardly bent portion 20 which lies between the guide bar 7 and the wear plate 5, the portion 20 being bent laterally at its lower end to provide a retaining portion 21, the portions 20 and 21 at the end of the bar providing a hook for retaining the stop bar in engagement with the guide bar.

When the door is swung to open position as shown in dotted lines in Fig. 1, the end portion 20 of the stop bar 18 moves from a point at the outer end of the guide bar 7, as shown in full lines in Fig. 1, to the inner end of the guide bar, as shown in dotted lines in Fig. 1. When the portion 20 of the stop bar 30 engages the tapered projection 13, the guide bar 7 is pressed outwardly against its own resilience and against the pressure of the spring 11 to permit the portion 20 of the stop bar to pass the projection 13 into the recess 14. When the end portion 20 of the stop bar is engaged in the recess 14, the door is latched in open position. The taper of the projection 13, however, will permit the stop bar to pass the projection 13, if sufficient pressure is applied to the door in a direction to close it.

Under normal conditions, the door will be held open until pressure is applied manually to the free edge of the door. Sometimes, however, the door may be subjected to heavy wind pressures which would force the stop past the yielding latch and free the door. In order to prevent damage to the door by heavy winds, means is provided by which the door may be positively held in open position. To accomplish this result, a locking device is provided for positively holding the inner end of the guide bar 7 against outward movement so that the end 20 of the stop bar is positively retained in the recess 20 until the manually operable locking device is released. The manually operable locking device is in the form of an elongated bar 22 which is pivotally supported on the pin 10 between the spring 11 and nut 12.

The elongated bar 22 is pivotally suspended adjacent its upper end from the pin 10 and has an inwardly bent upper end portion directly above the spring which in the normal position of the bar is clear of the

guide bar 7, so that it does not interfere with the movements of the bar 7 toward and from the door. The bar 22 has a lower end portion 24 bent inwardly at an angle, and normally resting against the face of the door, the aperture in the bar 22, through which the pin 10 passes, being of somewhat greater diameter than the pin so that the bar may be rocked toward and from the door. When the lower end of the bar 22 is pulled away from the door, the upper end 23 swings to a position immediately over the bar 7 and if the bar 22 be also moved laterally, the inner edge of the upper portion 23 of the bar is brought into full locking engagement with the guide bar 7 to positively lock the inner end of the bar against the face of the wear plate 5 so that the door will be positively locked in open position. In order to releasably retain the lock bar 22 in locking position, an angle bracket 25 is secured to the inner face of the door at a point spaced laterally from the normal vertical position of the bar 22 toward the hinged edge of the door. The bracket 25 has in its outer edge, a notch 26 in which the bar 22 may be retained. The pressure of the spring 11 tends to rock the lower edge of the bar 22 toward the face of the door and when the bar is in engagement with the notch 26, the spring serves to press the bar into the notch so that it will not be accidentally displaced therefrom.

It will now be apparent that the present invention provides a very simple and reliable door stop which operates normally as an automatic latch for yieldably retaining the door in open position, but which also provides means for positively locking the door in open position when desired.

It will also be evident that the device is composed of a minimum number of parts all of simple construction and inexpensive to manufacture and that the device can be very quickly and easily assembled and attached to a door.

What I claim is:

1. A stop device interposed between a swinging closure member and the structure in which it is mounted comprising a stop member movably connected to the closure member and structure, latching means engageable with said member for yieldably holding the closure member in an open position, and a manually operable locking member engageable with the latching means for positively holding the same against movement and locking the closure member in open position.

2. A stop device interposed between a swinging closure member and the structure in which it is mounted and comprising a stop bar movably connected at its opposite ends to the structure and closure member, a yielding latch member which the stop bar en-

gages as the closure member is opened for yieldingly holding the closure member in an open position, and a movable locking member engageable with the latch member for positively holding the same against movement to lock the closure member in open position.

3. A stop device interposed between a swinging closure member and the structure in which it is mounted and comprising a stop bar pivoted to one of said hingedly connected members and slidably connected to the other, a yielding latch member carried by the member with which said bar is slidably connected, which engages with the stop bar as the closure member is opened to yieldingly hold the closure member in open position, and a locking member movable into engagement with the latch member for positively holding the same against movement to lock the closure member in open position.

4. A stop device interposed between a swinging closure member and the structure in which it is mounted and comprising a combined guide bar and latch mounted on one of said hingedly connected members and extending substantially at right angles to the pivotal axis of the closure member, said bar being resilient and having one end fixed, the opposite end of said bar being movable toward and from the member to which it is attached and having a recess on the inner side thereof, and a stop bar pivoted at one end to the other of the hingedly connected members and having its opposite end slidable between the guide bar and the member to which it is attached and engageable in said recess to hold the closure member in open position.

5. A stop device interposed between a door casing and a door hinged thereto and comprising a combined guide bar and latch extending along a face of the door substantially at right angles to the pivotal axis thereof, said bar having its outer end secured to the door and its inner end movable toward and from the door, said bar being spaced from the face of the door and having adjacent its inner end a tapering projection on its inner side, a spring pressing the inner end of said bar toward the door, and a stop bar pivoted at one end to the casing and having its opposite end slidable between the guide bar and door, past said tapering projection when the door is opened, whereby the door is yieldably latched in an open position.

6. A stop device interposed between a swinging closure member and the structure in which it is mounted and comprising a wear plate secured to one of said hingedly connected members and extending substantially at right angles to the pivotal axis of the closure member, a resilient guide bar having one end fixed to said plate and the other movable toward and from the same, said bar having a tapering projection on the inner side thereof

adjacent its free end, and a stop bar pivoted at one end to the other of said hingedly connected members and having its opposite end bent laterally and retained between said guide bar and wear plate, the latter end of said stop bar being movable past said projection to the inner side thereof whereby the closure member is yieldingly retained in open position.

7. A stop device interposed between a door casing having a jamb and lintel and a door hinged to the jamb and comprising a combined guide bar and latch secured to the inner side of the door adjacent its upper edge, said bar having one end secured to the door and the opposite end movable toward and from the face of the door, the latter end of the bar having a recess on its inner side, a spring yieldably pressing the movable end of the bar toward the face of the door, and a stop bar pivoted at one end to the lintel and having at its opposite end a portion received between the guide bar and door, said end portion of the stop bar being engageable in said recess to yieldingly hold the door against movement.

8. A stop device interposed between a door casing and a door hinged thereto and comprising a combined guide bar and latch secured to the inner side of the door and extending substantially at right angles to the pivotal axis of the door, said bar having one end secured to the door and the opposite end movable toward and from the face of the door, the latter end of the bar having a recess on its inner side, a spring yieldably pressing the movable end of the bar toward the face of the door, a stop bar pivoted at one end to the casing and having at its opposite end a portion received between the guide bar and door, said end portion of the stop bar being engageable in said recess to yieldingly hold the door against movement, and a locking member carried by the door for engaging the movable end of said bar to positively retain the stop bar against movement.

9. A stop device interposed between a door casing and a door hinged thereto and comprising a combined guide bar and latch secured to the inner side of the door and disposed transversely with respect to the pivotal axis thereof, said bar having one end secured to the door and the opposite end movable toward and from the face of the door, the latter end of the bar having a recess on its inner side, a spring yieldably pressing the movable end of the bar toward the face of the door, a stop bar pivoted at one end to the casing and having at its opposite end a portion received between the guide bar and door, said end portion of the stop bar being engageable in said recess to yieldingly hold the door against movement, a locking member pivoted to the door and normally held by gravity in a position clear of said guide bar, said locking member being movable to a po-

sition engaging the movable end of the guide bar for positively holding the same against outward movement and locking said stop bar in said recess, and releasable means for retaining the locking member in locking position.

10. A stop device interposed between a door casing and a door hinged thereto and comprising a combined guide bar and latch secured to the inner side of the door and disposed transversely with respect to the pivotal axis thereof, said bar having one end secured to the door and the opposite end movable toward and from the face of the door, the latter end of the bar having a recess on its inner side, a pin projecting from the inner face of the door through the movable end of said guide bar, a spring carried by the pin for pressing said bar toward the door, a stop bar pivoted at one end to the casing and having its opposite end disposed between the guide bar and door and engageable in said recess when the door is opened, a locking member pivoted on said pin and movable to a position in which it holds said guide bar against outward movement, whereby the stop bar is locked in said recess and the door is positively held against closing movement.

11. A stop device interposed between a door casing and a door hinged thereto and comprising a wear plate attached to the inner side of the door and extending transversely with respect to the pivotal axis thereof, a pin projecting from said plate adjacent the inner end thereof, a guide bar secured at its outer end to said wear plate and having its inner end slidable on said pin, said bar being bent to provide a tapering projection on its inner side and a recess between said projection and pin, a spring carried by the pin and pressing the inner end of the guide bar against the wear plate, and a stop bar pivoted at one end to the lintel and having its opposite end bent to hook form and extending between the wear plate and guide bar, said stop bar moving past said projection as the door is opened and being yieldingly retained in said recess to hold the door in open position.

12. A stop device interposed between a door frame having a jamb and lintel, and a door hinged to the jamb and comprising a wear plate attached to the inner side of the door adjacent its upper edge, a pin projecting from said plate adjacent the inner end thereof, a guide bar secured at its outer end to said wear plate and having its inner end slidable on said pin, said bar being bent to provide a tapering projection on its inner side and a recess between said projection and pin, a spring carried by the pin and pressing the inner end of the guide bar against the wear plate, a stop bar pivoted at one end to the lintel and having its opposite end bent to hook form and extending between the wear plate and guide bar, said guide bar moving

past said projection as the door is opened, and being yieldingly retained in said recess to hold the door in open position, a locking bar pivoted to said pin outwardly of the spring, said bar having an inwardly projecting upper end which is held in a position clear of the guide bar when the locking bar is in a vertical position, but which is moved to a locking position overlying the guide bar when the lock bar is swung laterally, and means on the door for releasably retaining said locking bar in its inclined locking position.

In testimony whereof I affix my signature.

HARRIS M. WHITCOMB.
